UNITED STATES PATENT OFFICE.

JOHN H. THWAITES, OF LONDON, ENGLAND.

REFUSE-DESTRUCTOR FURNACE.

1,050,253

Specification of Letters Patent. Patented Jan. 14, 1913.

Application filed May 22, 1911. Serial No. 628,306.

To all whom it may concern:

Be it known that I, JOHN HUBERT THWAITES, a subject of the King of Great Britain, residing at Clock House, Arundel street, Strand, London, England, engineer, have invented new and useful Improvements in Refuse-Destructor Furnaces, of which the following is a specification.

My invention relates to an improved form 10 of those refuse destructor furnaces which are provided with a plurality of grate cells and separate ashpits for each cell and with a hollow furnace front surrounding the firing and clinkering openings of the grate 15 cells, said hollow furnace fronts communicating with the ashpits of said cells and having perforations through which the air heated in said fronts passes to the furnace.

A single grate cell of the improved refuse 20 destructor furnace of my invention is illustrated more particularly in the accompanying drawings in which—

Figure 1 shows a sectional plan view of a 25 continuous grate system and combustion chamber in which the grate cells are separated by air cooled troughs; Fig. 2 shows a section on the lines A—B of Fig. 1; Fig. 3 shows a detail view of a separating trough; Fig. 4 shows a sectional side view, partly 30 broken away, through a single grate cell on the line A—B of Fig. 5; Fig. 5 shows an internal front view on the line C—D of Fig. 4, and Fig. 6 shows a plan view, partly broken away, of Fig. 4.

As illustrated I construct the arched bars 35 17 and supporting jam blocks 10 of the firing and clinkering openings to the grate cells of hollow castings 10 provided with perforations 11 facing away from the clinkering doors 12, shown in dotted lines in Figs. 4 and 6. These hollow castings 10 are

in communication with the ashpits of their grates through the openings 13 under the dead plates 14, so that a proportion of the air used to force the draft passes through 45 said castings 10 and discharges through said perforations 11, thus keeping said castings reasonably cool and supplying at the same time a small supply of consequently hot air to insure perfect combustion above the fire. 50 The castings which form the jam blocks of said firing and clinkering openings communicate with the perforated inverted troughs 3 lining the grate cells through the 55 passages 16. The insides of said troughs are open to the ashpits 2 while the air passing from the ashpits through the perforations 4 in the sides of said troughs help the combustion of the fuel upon the grates 1. 60

What I claim is:

In a refuse destructor furnace the combination of a plurality of grate cells with the firing and clinkering openings with separate ashpits for each of said grate cells, hollow arched bars and supporting jam blocks surrounding the firing and clinkering openings of said cells, said hollow arched bars and supporting jam blocks being provided with air holes facing away from said firing and clinkering openings and with passages connecting the interior of said jam blocks with the ashpits of their grate cells, perforated inverted air cooled troughs lining the walls of said cells with passages leading from said troughs to said jam blocks. 70 75

In testimony whereof I have signed my name to this specification in the presence of the two subscribing witnesses.

J. H. THWAITES.
